CAP SCREW

Paul F. Pick, West Hartford, Conn., assignor to The Allen Manufacturing Company, Hartford, Conn., a corporation of Delaware

Filed Apr. 22, 1965, Ser. No. 84,903

Term of patent 14 years

(Cl. D54—9)

FIG. 1 is a side elevational view of a cap screw showing my new design;

FIG. 2 is an enlarged top plan view thereof;

FIG. 3 is an enlarged bottom plan view thereof; and

FIG. 4 is a perspective view thereof.

The dominant features reside in the solid line portion.

This is a continuation-in-part of design application Serial No. D. 78,510, filed February 4, 1964, now abandoned.

I claim:

The ornamental design for a cap screw, as shown and described.
